UNITED STATES PATENT OFFICE.

ISAAC ROSENFELD, OF MALDEN, MASSACHUSETTS.

PROTECTOR FOR HATS AND CAPS.

1,331,876.

Specification of Letters Patent. Patented Feb. 24, 1920.

Application filed March 17, 1919. Serial No. 283,079.

To all whom it may concern:

Be it known that I, ISAAC ROSENFELD, a citizen of the United States, and a resident of Malden, county of Middlesex, State of 5 Massachusetts, have invented an Improvement in Protectors for Hats and Caps, of which the following is a specification.

In selling hats and caps at retail, a customer frequently tries on several of these 10 articles before deciding on a purchase, and consequently he tries on several hats which he does not purchase.

This practice is believed to be unhygienic and liable to result in the communication 15 of skin diseases from one to another. Moreover, customers, as a rule, prefer not to place hats on their heads, which have been on the heads of others, for other reasons.

The object of my invention is to provide 20 a simple, convenient and effective means for protecting the sweat band of a hat or cap before it is sold at retail, which will not substantially effect the size of the hat, whereby each customer may be assured, 25 that, when he tries on a hat, his head does not come into actual contact with the same surface as that which came into contact with the head of the customer who may have previously tried it on.

I accomplish this object by providing 30 within the hat or cap a package of thin papers, so arranged that the sheets thereof may be successively turned into a position to cover the sweat band, or other portion 35 of the hat which fits on the head, while it is being tried on by the prospective purchaser, the arrangement being such that the sheets may be either successively torn off, so that a fresh sheet may be employed 40 for the next customer, or the whole package may be readily removed in case the hat is sold.

I accomplish these objects by the employment 45 of the means shown in the accompanying drawing in which:

Figure 1 is a longitudinal sectional view of a cap provided with an embodiment of my invention.

Fig. 2 is a transverse sectional view 50 thereof.

Fig. 3 is an enlarged detail sectional view thereof.

Fig. 4 is a detail sectional view of a somewhat modified form of the invention.

55 While my invention is applicable to almost any form of hat or cap, it is shown in

Figs. 1, 2 and 3, as applied to a common form of cap *a*, having the usual leather sweat band *b*, attached thereto at the brim.

According to my invention, I provide a 60 package *c*, composed of strips of thin, tissue paper and secured together by eyelets *d*, along one longitudinal edge, the length thereof being sufficient to extend approximately half the length of the sweat band 65 and the width thereof being slightly greater than the width of the sweat band.

This package is arranged with its edge having the eyelets *d* therein within the unattached edge portion of the sweat band, so 70 that it extends from points approximately at the middle at one side, about the front, to the corresponding point at the opposite side.

The edge portion of the sweat band may 75 be provided with eyelets *e* in its edge portion, one at the middle of the front and two at the middle of the sides. The eyelets *d* are correspondingly arranged in the package, and fasteners *f*, which may be of the 80 ordinary "McGill" type, are passed through the corresponding eyelets *d* and *e* to attach the package of papers to the sweat band, as shown in Figs. 1, 2 and 3.

A similar package *c'* may be applied in 85 like manner to the rear half of the sweat band, and secured in position by fasteners *f'*, in a manner similar to that before described.

In case a cap, thus fitted, is to be tried on, 90 the saleman turns down the innermost strip, or sheet of each package, so that it is bent sharply over the edge of the sweat band and lies against the surface thereof, as shown in Figs. 2 and 3, completely covering 95 the outer surface thereof. As thus arranged, when the cap is tried on, the head of the person on which the cap is placed cannot come in contact with the surface of the sweat band, as will be obvious.

As each sheet of paper is very thin, it 100 will not appreciably affect the size of the cap when it is tried on. If the customer decides not to purchase a particular cap, the sheets which were turned down will be torn 105 off, so that the next sheet may be turned down when the cap is to be tried on the next customer, or if the hat is purchased, the package will be entirely removed.

While the paper package may be conveniently attached to the sweat band, as above described, when the cap is not pro-

vided with a sweat band, the advantages of my invention may be secured by securing the package directly to the cloth of the cap by the employment of small wire staple fasteners *g*, as indicated in Fig. 4. Such fasteners may be applied without injury to the material and may be easily removed.

The manner in which this form of my invention is employed is similar to that already described, the sheets being turned down to cover the rim portion of the hat which fits on the head, as indicated.

I claim:

1. In combination with a hat or cap, a package, composed of a plurality of thin paper strips, disposed therein at a substantial distance above the rim thereof, and extending about the front portion thereof, attaching means at the lower edge of said package for securing it in said position, to permit each strip to be successively turned down to cover the head engaging portion of

the hat or cap above which the package is disposed.

2. In combination with a hat or cap having a sweat band attached adjacent its rim, a package composed of a plurality of strips of thin paper removably attached at one longitudinal edge to the free edge portion of the sweat band, normally to extend thereabove, and arranged to be successively folded down over said band.

3. In combination with a hat or cap having a sweat band attached adjacent its rim, a package of thin paper strips attached together at one longitudinal edge and disposed with their attached edge portion within the free edge portion of the sweat band, and means for temporarily connecting the overlying portions of the package and band.

In testimony whereof, I have signed my name to this specification.

ISAAC ROSENFELD.
